UNITED STATES PATENT OFFICE.

MARSH PITZMAN, OF ST. LOUIS, MISSOURI.

INTERNAL-COMBUSTION ENGINE.

Application filed November 12, 1921. Serial No. 514,523.

To all whom it may concern:

Be it known that I, MARSH PITZMAN, a citizen of the United States of America, residing at the city of St. Louis, State of Missouri, United States of America, have invented a certain new and useful Internal-Combustion Engine, of which the following is such a full, clear, and exact description as will enable any one skilled in the art to 10 which it appertains to make and use the same, reference being had to the accompanying drawings, forming part of this specification.

My invention relates to means for improving the operation of internal combustion engines and the particular embodiment herein described is designed for application to engines of the ordinary water cooled type used for driving vehicles.

20 In such engines, the water from the radiator is usually supplied to the engine water jacket at a point adjacent to the front cylinder and in the case of single block engines may circulate from this point past all 25 of the cylinders. Since the water is at lower temperatures when passing the front cylinder than when passing other cylinders its cooling effect is uneven and if sufficient for the rear cylinders may be too great 30 under average conditions for the front cylinder.

Another difference in cooling exists in that the air currents passing the engine due to the movement of the vehicle and the 35 operation of the fan are more effective on the front and rear cylinders than on intermediate ones. Uneven cooling of cylinders results in numerous disadvantages such as uneven distribution and quantities of fuel 40 charges and inefficient combustion accompanied by fouling of spark plugs in cylinders which are maintained at too low a temperature. Also in multiple cylinder engines in which the cylinders are linearly arranged one side of both the front and rear 45 cylinders is adjacent to other cylinders, a condition which results in a tendency to maintenance of a higher temperature in these portions than on the opposite sides 50 which are exposed. This causes some cylinder distortion in operation and consequent impairment of compression.

It is the object of my invention to provide means for overcoming the hereinabove 55 described unsatisfactory temperature conditions and produce a more even operating

temperature throughout all cylinders and throughout the walls of the front and rear cylinders.

In the accompanying drawings, Figure 60 1 is a side view of one type of engine showing my invention applied thereto; Figure 2 is a top plan view of the engine shown in Figure 1; Figure 3 is a fragmentary view showing partly in section a cylinder wall 65 and adjacent water passage and applied insulating means in accordance with my invention; Figure 4 is an enlarged sectional view of the insulator and retaining means applied to the front of the engine as shown 70 in the other figures.

1 represents a water cooled engine of the single block type and 2 a water passage adjacent to a part of one cylinder. 3 is a water conduit by which water is returned 75 from the engine water jacket to the radiator (not shown). 4 indicates the fan for drawing in air through the radiator and propelling it past the engine.

In the embodiment of my invention illustrated, I achieve the objects hereinabove set forth by applying to the front of the engine and to the rear thereof, sheets of insulating material 5, such as asbestos for example, and these sheets may be held in position and protected by sheets of brass 6 which in turn may be connected by wires 7 serving to clamp the insulating sheets against the engine walls and hold them in 80 position.

The sheets 6 are made to embrace only a sufficient portion of their adjacent cylinders (usually about one half of the front cylinder) to cause the cylinder temperatures to be maintained at the desired point, a result which they produce both by eliminating the effect of external air currents and restricting the radiation of heat from the portions of the engine walls with which they are in contact.

100 The air currents under the engine hood produced by the fan and the motion of the vehicle are, of course, less effective on the rear cylinder than on the front cylinder adjacent the fan but are more effective on 105 the rear cylinder than on intermediate cylinders due to the eddy currents set up and the greater area exposed. It will usually be necessary to insulate a smaller area of the surface of the rear cylinder than of the front cylinder and due to less effective cooling by 110 the water and to other factors, insulation of

the rear cylinder may in some instances be unnecessary.

By means described, I am able to very greatly improve the operation of most if not all of the common type of automobile engines and accomplish this result by inexpensive means which are easily applicable.

My invention has the further advantage that the degree of insulation can be varied for each engine to compensate for existing temperature producing and dissipating factors which are of variable degree and effect in different engines and under varying conditions.

Having fully described my invention what I claim as new and desire to secure by Letters Patent of the United States is:

1. The combination with an internal combustion engine, of means adapted to restrict the radiation of heat from a selected portion only of the lateral walls of the engine cylinders to equalize the operating temperatures of the said cylinders.

2. The combination with a multiple cylinder internal combustion engine, of heat insulating means applied to a selected portion only of the lateral wall surface of the engine cylinders to restrict the radiation of engine developed heat therefrom, the remaining lateral cylinder wall surface of the engine being uninsulated.

3. The combination with an internal combustion engine, of a fan producing air cur-

rents directed thereupon, and means for restricting the cooling effect of the fan currents on a portion of the lateral cylinder wall surface of the engine to a greater degree than on other portions of said surface.

4. The combination with a multiple cylinder internal combustion engine, of a fan producing air currents directed thereupon, heat insulating means applied to the portion of the engine cylinder wall surface nearest the fan, the lateral wall surface of intermediate cylinders being uninsulated from fan currents.

5. The combination with a multiple cylinder internal combustion engine, of heat insulating means applied to the lateral wall surfaces of the front and rear cylinders only to restrict the radiation of engine developed heat therefrom, the intermediate cylinders being uninsulated.

6. The combination with a multiple cylinder internal combustion engine, of means forming passages adjacent to the engine cylinder for the circulation of cooling medium, and heat insulating means applied to a selected portion only of the exterior of the lateral cylinder wall surface of said engine to increase the operating temperature of a selected cylinder or cylinders less than all.

In testimony whereof, I have hereunto set my hand and affixed my seal.

MARSH PITZMAN. [L. S.]
